UNITED STATES PATENT OFFICE.

FRANK L. PAGE, OF INDIANAPOLIS, INDIANA.

GOVERNING-VALVE.

1,294,151.

Specification of Letters Patent. Patented Feb. 11, 1919.

Application filed March 20, 1916. Serial No. 85,387.

To all whom it may concern:

Be it known that I, FRANK L. PAGE, a citizen of the United States, and a resident of Indianapolis, county of Marion, and State of Indiana, have invented a certain new and useful Governing-Valve; and I do hereby declare that the following is a full, clear, and exact description thereof, reference being had to the accompanying drawings, in which like letters refer to like parts.

The object of this invention is to provide a valve which may be used by interchanging the parts thereof for five different purposes so that the same valve may be used in place of five different types of valve. The valve construction herein shown, by simply interchanging the parts may be used as an excess pressure governor valve or a constant pressure governor valve or a pressure reducing valve or as a relief or pop safety valve or as a condenser governor valve, as desired. Another feature of the invention is the valve seat which may be reversed should one side wear out, or be easily replaced if both sides are worn. Other than the above features of this invention, the construction of the valve is extremely simple and durable. There is no complicated mechanism nor any parts which are liable to get out of order and should any of the parts wear out, the construction is such that they may be easily and cheaply replaced.

The invention consists chiefly of a spring-controlled valve in connection with one or more compression chambers and pistons, and means for conducting the pressure to said chambers in such a way as to regulate the valve for the purpose desired.

The full nature of the invention will be understood from the accompanying drawing and the following description and claims:

In the drawings, Figure 1 is a central vertical cross section through the valve mechanism showing it as an excess pressure governor valve. Fig. 2 is the same as Fig. 1, showing it as a constant pressure governor valve. Fig. 3 is a diagram of a steam and water pump showing the valve mechanism thereon as used in Figs. 1 and 2. Fig. 4 is a vertical central cross section of the pressure reducing valve. Fig. 5 is a vertical central cross section of the relief valve. Fig. 6 is a vertical central cross section of the

condenser governor valve. Fig. 7 is a diagram showing the valve used as a condenser governor valve in connection with a water pump and ammonia line. Fig. 8 is a side elevation of a modified form of the valve.

Fig. 1 of the drawings shows a valve housing 10 having an inlet 11 and outlet 12. A web 13 extends downwardly from the outlet and upwardly from the inlet and has a valve seat 14 secured therein so that the steam entering the inlet 11 will have to pass through the valve seat 14 in order to pass into the outlet 12. Secured on the upper side of the housing 10 there is a spring housing 15 and on the lower side of the housing 10 there is secured a cap 16 having an inlet port 17. Within the housing 10 there are bushings 18 in which there is a pair of pistons 19 and 20. Integral with the piston 19 there is a valve 21 adapted to seat in the valve seat 14. A hollow tube 22 is secured to the pistons 19 and 20, passing through the valve seat 14 and keeping said pistons at all times equidistant from each other. In said tube there are ports 23 which allow the steam entering the steam chamber to pass through said tube into the spring housing 15. At the upper portion of said spring housing there is an adjustable spring retaining disk 24. Between the piston 20 and the retaining disk 24 there is a compression spring 25 adapted to exert a downward pressure on said piston. Against the upper side of said disk there is an adjusting screw 26 having a lock nut 27 thereon adapted to pass through the upper end of the housing 15 so as to hold the disk 24 at a given position against the spring 25. On the lower end of the piston 19 there is a plug 28 adapted to prevent the steam entering through the tube 22 to pass into the chamber 29.

The valve shown in Fig. 1 is adapted to be used as an excess pressure governor valve, as shown in the diagram of Fig. 3. There is a feed water pump 30 which sucks in the water through a pipe 31 and forces it out through a pipe 32 to which is connected a pipe 33 which enters the valve at the inlet port 17. The steam which operates the pump passes through the steam line, entering the valve at the inlet 11, passing through the outlet 12 into the steam chamber of said pump.

The operation of the mechanism is as follows:

When it is desired to maintain pressure in the discharge line of the pump at a certain number of pounds in excess of the steam pressure, the valve is placed in the steam line, as shown. The hollow tube 22 permits the steam to enter the chamber 34 above the piston 20 and exert a pressure downwardly on said piston. Therefore, there would be a downward pressure adapted to open the valve, exerted by both the steam pressure and the spring 25, while on the other hand, the water entering chamber 29 through the port 17 will exert an upward pressure against the piston 19 which will have a tendency to close the valve. Therefore, it will be readily seen that as the two pistons are balanced with no tension on the spring the valve would maintain a pressure in the outer or discharge line 32 equal to the steam pressure, but if there is a tension upon the spring 25 the pressure in the pipe line 32 will always be equal to the steam pressure plus the pressure exerted by the spring. Therefore, when the water pressure becomes greater than the steam pressure plus the spring pressure, the valve will be closed and the steam shut off until the water pressure is reduced. Therefore, the steam pressure regulates this and at the same time permits a greater water pressure, depending on the pressure at which the spring is set. In this way, the discharge pressure of any pump may be regulated by putting more or less tension on the spring while the steam pressure entering the inlet 11 may remain at a less pressure.

Fig. 2 shows the valve construction as a constant pressure governor valve, the only change that is made being that the tube 22 is closed at both the top and the bottom by plugs 28 and 40. It is used in the same way as the valve shown in Figs. 1 and 3, but in this type of valve the steam cannot pass into the chamber 34 and, therefore, the water pressure in the chamber 29 must be greater than the pressure of the spring in order to close the valve and shut off the steam. This valve is used when it is desired to maintain a certain fixed pressure in the discharge line 32 from any kind of pump. Therefore, if it is desired to maintain a certain pressure in the discharge line 32, it is simply necessary to exert a tension on the spring which will give the desired pressure. Should the pressure in the chamber 29 exceed the desired pressure, it would overcome the spring pressure and close the valve, but as soon as it drops below that pressure, the spring would again force the valve open. This type of valve is especially adapted for controlling pumps operating boiler tube cleaners because the discharge line 32 is alternately opened and closed and this valve keeps the pressure in line 32 constant.

The pressure reducing valve shown in Fig. 4 has a plug 41 in the end of the tube 22 which prevents the steam from entering the chamber 34, but the piston 19 has a passage-way 42 which permits the steam to pass through the tube 22 into the chamber 29. There is a plug 43 adapted to close the port 17. The steam or other fluid entering the valve will pass through the ports 23 and tube 22 into the chamber 29 and exert a downward pressure against the cylinder 19, which will have a tendency to close the valve while the pressure exerted by the spring 25 will have a tendency to open the valve. Therefore, the pressure of the steam entering the steam chamber must overcome the pressure of the spring in order to pass on through the valve. The steam pressure leaving the valve will always be equal to the spring pressure. Therefore, any desired pressure may be obtained by adjusting the spring to that pressure, for if more than the desired pressure should pass through the valve seat, the pressure against the piston 19 would overcome the pressure on the spring and close the valve. This device is used when it is desired to reduce a constant or fluctuating pressure to a lower constant pressure.

Fig. 5 shows the device used as a relief valve. The construction of this valve is the same as that shown in Fig. 4, excepting that the pistons 19 and 20 are reversed and valve 21 is, therefore, on the opposite side of the valve seat and the tension of the spring exerts a pressure which tends to force the valve against the seat and thereby close it. The steam inlet 11 is connected with a steam boiler or the like and the outlet 12 is open. When the inlet pressure becomes excessive or too great in the chamber 29, it will overcome the spring 25. If the inlet pressure becomes greater than the pressure of the spring, the valve will be opened and will remain open until the inlet pressure falls below the pressure exerted by the spring.

Fig. 6 shows the valve used as a condenser governor valve. The construction of this valve is the same as shown in Fig. 5 excepting that both ends of the tube are plugged and the chamber 29 is opened to a pipe line 45. This type of valve is especially adapted to be used for governing condensers in ice plants when it is desired to control the ammonia pressure thereof. Fig. 7 shows a diagram thereof. The steam enters the pump 30 through the inlet 11 passing through the valve and outlet 12. The water is forced through the pipe 32 into a tank 46 in which there are ammonia coils 47, the pipe line 45 being connected to said coils so as to permit the pressure exerted by the ammonia to be applied against the piston 20 for opening the valve. As the valve is balanced, the given pressure exerted

- by the spring will close the valve as long as the ammonia pressure remains below that pressure, but it will open the valve and permit more water to pass into the condenser
- 5 when the ammonia pressure rises above the given pressure, which will reduce the ammonia pressure. This does away with the necessity of keeping water constantly flowing over the ammonia piping or coils or
- 10 into the condensers in order to keep the ammonia pressure down. The valve may be placed on the water line 32 if there is no pump used and the same result will be obtained.
- 15 Fig. 8 shows a modified form of the valve. In this form instead of the steam pressure passing through a hollow tube into the chambers at each end of the pistons, it passes through the pipe 48, valves 49 and pipes 50 into the chambers which operates the mechanism in the same manner. Instead of inserting a plug at one or the other, or both ends of the tube, the valves 49 are operated to obtain the same results.
- 25 It will, therefore, be readily seen that this valve mechanism may be used for a number of different purposes and produce a number of different results by simply adding or reversing the parts thereof and it is
- 30 so constructed that each part may be replaced separately and independently of every other part.
- The invention claimed is:
1. A valve construction having an inlet and outlet, a valve seat between said inlet and outlet, cylinders on each side of said valve seat, pistons in said cylinders, passageways through said pistons, a hollow tube adapted to pass through said valve seat for rigidly connecting said pistons, having ports therein whereby pressure may be conducted to the opposite ends thereof, means on one of said pistons for closing said valve, means for opening or closing said passageways, and an inlet in one of said chambers whereby an external pressure exerted on said pistons will operate said valve. 50
2. A valve construction having an inlet and outlet, a valve chamber between said inlet and outlet, a partition in said chamber, a valve seat removably secured in said partition, compression chambers on each side of valve chamber, a connecting rod extending through said valve chamber, pistons removably secured to said connecting rod on each side of said valve seat and a valve on one of said pistons. 55
3. A valve construction having an inlet and outlet, a valve chamber between said inlet and outlet, a partition in said chamber, a valve seat removably secured in said partition, compression chambers on each side of valve chamber, a connecting rod extending through said valve chamber, pistons removably secured to said connecting rod on each side of said valve seat and a valve on one of said pistons. 60
4. A valve construction having an inlet and outlet, a valve chamber between said inlet and outlet, a reversible valve seat in said chamber, compression chambers on each side of said valve chamber, interchangeable pistons in said compression chambers, a valve on one of said pistons for engaging said valve seat, and interchangeable cylinder heads adapted to be removably secured to said compression chambers. 65
5. A valve construction having an inlet and outlet, a valve chamber between said inlet and outlet, a reversible valve seat in said chamber, compression chambers on each side of said valve chamber, interchangeable pistons in said compression chambers, a valve on one of said pistons for engaging said valve seat, interchangeable cylinder heads removably secured to said compression chambers, one of said heads having an inlet, 70
- 35 and a spring in the other cylinder head for exerting a pressure against one of said pistons. 75
